DESIGN FOR AN AERODYNAMIC TIRE

Albin K. Peterson, Redondo Beach, Calif.

Application January 21, 1946, Serial No. 125,817

Term of patent 14 years

(Cl. D90—20)

To all whom it may concern:

Be it known that I, Albin K. Peterson, a citizen of the United States, residing at Redondo Beach, county of Los Angeles, and State of California, have invented a new, original, and ornamental Design for an Aerodynamic Tire, of which the following is a specification, reference being had to the accompanying drawing, forming part thereof.

Fig. 1 is a side elevation of an aerodynamic tire embodying my new design.

Fig. 2 is a section through a portion of the tire, the section being taken along plane II—II of Fig. 1.

Fig. 3 is a section through a portion of the tire,

the section being taken along plane III—III of Fig. 1.

I claim:

The ornamental design for an aerodynamic tire, substantially as shown.

ALBIN K. PETERSON.
